UNITED STATES PATENT OFFICE.

TRISTRAM D. BROWN, OF CANANDAIGUA, NEW YORK, ASSIGNOR TO
LEONARD A. PARKHURST, OF SAME PLACE.

DESIGN FOR A BAIL-EAR.

SPECIFICATION forming part of Design No. 24,387, dated June 11, 1895.

Application filed May 11, 1895. Serial No. 548,995. Term of patent 7 years.

To all whom it may concern:

Be it known that I, TRISTRAM D. BROWN, a citizen of the United States, residing at Canandaigua, in the county of Ontario and State of New York, have invented and produced a new and original Design for a Bail-Ear; and I do hereby declare the following to be a full, clear, and exact description of the same, reference being had to the accompanying drawings, forming a part thereof.

In the accompanying drawings, Figure 1 is a perspective view of the bail-ear. Fig. 2 is a sectional view of the ear.

The leading features of my design consist in two parts set at an angle to each other, one part being substantially oval in shape and the other part being in the shape of a conventionalized clover leaf, a web extending into each part, and the indentations in the oval shaped part, all as shown in Fig. 1 of the drawings.

The ear is made of a single piece of sheet

metal pressed into the desired shape. The part 1, is made in the shape of a conventionalized clover leaf, with a perforation 2, in each leaf. The part 3, is substantially oval in shape, and is set at an angle to the part 1. Part 3, is provided with a perforation 4, and the indentations 5, 5, one on each side of the perforation 4, and a little below the same. The web 6, is pressed in the metal and extends well into each of the said parts 1, and 3.

Having described my invention, what I claim as new, and desire to secure by Letters Patent, is—

The design for a bail ear substantially as shown and described.

In testimony whereof I affix my signature in presence of two witnesses.

TRISTRAM D. BROWN.
